ROBERT ALEXANDER STEPS, OF LOS ANGELES, CALIFORNIA.

CENTRIFUGAL CONTROL.

Application filed May 23, 1927. Serial No. 193,647.

In operating centrifugal machines in the industries where they are used, several simple but important operations are usually performed manually, and are repeated for each 5 cycle of the centrifugal. An important feature of these operations is that they should be performed one after the other with a correct interval of time intervening between them. For instance, in a sugar factory, after 10 the massecuite is charged into the centrifugal, and same is started spinning, the operator allows a certain period of time to lapse and he then turns on the automatic washing machine to wash the sugar while the 15 centrifugal is spinning at full speed; after the lapse of a further period of time he throws the gate leading from the curbing, so as to effect a separation between the original liquor and the wash liquor spun off by 20 the centrifugal into the curbing; and after the lapse of a still further period of time he cuts off the power, applies the brake and brings the centrifugal to rest, which completes the cycle for that charge. As previously stated, the operator should allow a 25 definite period of time to elapse between each of these operations. If these periods are kept uniform from cycle to cycle, the resulting product discharged from the centrifugal will 30 be uniform, but if they are not kept uniform there will be a tendency for the product to vary, and this is undesirable. Obviously the instincts and faculties of the man who operates the centrifugals is not always an accurate means for measuring time, and therefore there is a corresponding variation in the 35 time periods which he allows to elapse in his usual manual mode of performing the above operations.

One of the objects of this invention is to provide a simple, accurate and dependable arrangement and combination of parts whereby the foregoing operations will be automatically performed in accurate time sequence, thereby securing greater accuracy in the measurement of the above periods of time, and also securing some saving in labor by transferring the above described operations from the manual operator to the control equipment.

Other objects and benefits of this invention will be made clear by the accompanying drawings, the following detailed description, and the accompanying claims.

In the accompanying drawings Fig. 1 is a vertical section through one 55 form of time measuring equipment which constitutes a part of my invention.

Fig. 2 is a similar section taken at right angles to Fig. 1.

Fig. 3 is a transverse section taken on lines 60 x^3-x^3 , see Fig. 4.

Fig. 4 is an enlarged sectional view showing the details of the parts located near the top of Fig. 1.

Fig. 5 is a similar enlarged sectional view showing the details of the parts located near the bottom of Figs. 1 and 2.

Fig. 6 is a diagrammatic view of a belt driven centrifugal machine equipped with 70 my invention.

Fig. 7 is a diagrammatic view of a direct connected electric driven centrifugal equipped with my invention.

Fig. 8 is a fragmental view showing a section taken on line x^8-x^8 of Fig. 7.

Fig. 9 is a partial section showing a detail that will be hereinafter described.

Fig. 10 is similar to Fig. 9 but shows the relation of the parts after they have been 80 actuated from the position shown in Fig. 9.

Fig. 11 is a side view of the detail illustrated in Figs. 9 and 10, this view being a section along the lines $x^{11}-x^{11}$ in Fig. 10.

The broader aspects of this invention are 85 best illustrated in Figs. 6 and 7. Fig. 6 shows same in combination with a standard belt driven centrifugal, whereas Fig. 7 shows it in combination with a standard direct connected electric motor driven centrifugal. 90 The invention however is applicable irrespective of the particular mode of drive, and in addition to the drives shown, a water drive, or any other mode of drive may be used, the corresponding and equivalent parts 95 in these various drives being apparent.

In Figs. 6 and 7 the centrifugal proper consists of basket 1 carried by the rotatable spindle 2 which is suspended from a stationary head member 3, the latter being in 100 turn supported by structural steel which is omitted from the drawings for clearness.

The rotatable basket 1 is surrounded by a stationary curbing 4, having a liquor drain 5 adapted to direct liquor from the curbing 105 on to the movable gate 6. This gate is pivotally mounted on pin 7, and in one position shown by the full lines in Figs. 6 and 7 it

directs said liquor into trough 8, whereas in its other position shown by the dotted lines this gate directs the liquor into the neighboring trough 9.

5 In connection with the centrifugal there is usually provided some form of washer, or washing equipment. Any form of automatic washer may be used in connection with this invention, but I have illustrated one well known form designated by the reference numeral 10 in Figs. 6 and 7. All the details of this washer are fully described in the United States Patent No. 1,439,676, dated December 19, 1922, issued to W. W. Hartman, 15 and reference should be made to said patent for desired details of construction. Water is supplied to these washers through a connection 11, the piping to same being omitted in the drawings. Within the washer box 20 there is a valve 129, see Fig. 11, for starting and stopping the flow of water through the washer. On top of the box there is a starting lever 12, and when same is thrown to its "going" position this automatically opens 25 the valve and allows the water to flow through the nozzle arm 12^a to set up a spray 13 impinging on the basket 1. At the same time this nozzle arm is started oscillating in such a manner as to sweep the spray 13 up 30 and down, from the top of the basket to the bottom within the limits indicated by the lines 13^a and 13^b, Figs. 6 and 7. These washers also have automatic measuring means, whereby the quantity of water dispensed by the washer is measured, and the washer automatically stops when the measured amount of water is dispensed. The amount can also be readily adjusted and changed to suit the requirements. As previously stated however these washers are 40 standard equipment, well known in the industries, and fully illustrated and described in the above mentioned Hartman patent. For that reason the details of this particular 45 washing equipment are not repeated in the drawings submitted herewith.

Near the top of spindle 2, and rigidly fastened thereto, there is usually a pulley or drum member 14.

50 When the centrifugal is belt driven, the most usual arrangement at present in use is illustrated in Fig. 6. In this form the driving means consists of a driving pulley 15, and quarter twisted belt 16 running 55 around pulleys 14 and 15, and being guided by idler pulley 17. Through this pulley 15, but without being fastened thereto, runs the constantly rotating power shaft 18, which may properly be designated as the power 60 supply, or source of power, for the reason that it is this shaft which supplies the power to the said driving means when connection is established between them. For the purpose 65 of connecting and disconnecting said driving means to the said power shaft, for starting

and stopping the centrifugal, there is provided a standard clutch 19, one part 20 of which is secured to rotate with power shaft 18, and another part of which is arranged in the usual manner to connect and disconnect frictionally with driving pulley 15, on the inner face of same. This clutch is standard however, and since its details are well known in the industry, and form no part of this invention, it is 70 shown only diagrammatically in the drawings. As a part of this standard clutch, and for the purpose of operatively connecting and disconnecting it with the driving pulley 15, there is a sector 21 pivotally mounted at 75 22, and having gear teeth 23 at one side and a shifting pin 24 at the other side, the latter being adapted to engage and disengage the clutch in the usual manner when the sector 21 is rocked to and fro on its pivotal support 80 22. There is also a shaft 25 having a gear pinion 26 at one end, meshing with gear teeth 23 on the sector, and a handwheel 27 at the other end of said shaft 25. The handwheel 27 is of course conveniently located for 85 the operator, so that he can throw same one way or the other as he stands in his usual position before the centrifugal. As he rocks this handwheel to one side or the other the pinion 26 rocks the sector 21 to engage and 90 disengage the clutch with driving pulley 15, as indicated. It is this mode of connecting and disconnecting the power source or power shaft 18 with the driving means, that is used 95 in starting and stopping the centrifugal. 100

In order to bring the centrifugal rapidly to rest after the power is disconnected, a standard type of brake is furnished on all commercial centrifugals. One type of such standard brake is diagrammatically shown 105 in Figs. 6 and 7 and comprises the brake shoe or shoes 28 adapted to frictionally engage the inner face of the pulley or drum 14. The brake shoes are connected with the usual mechanism terminating in brake lever 29, the 110 details of such brake mechanism being omitted from the drawings for the reason that same are well known in the industry, and also because this invention does not depend 115 upon the particular details of the brake.

When the centrifugal is driven by the direct connected electric motor drive, shown 120 in Figs. 7 and 8, instead of the belt drive previously described, then the driving means consists in the electric motor 30, instead of the driving pulley and belt; the power source or power supply consists in the electric power line 31, Fig. 8, instead of the constantly rotating power shaft previously described; and the means for connecting and disconnecting 125 the driving motor consists in the standard switch box 32, instead of the clutch, and the standard switch mechanism in this switch box can be opened and closed by the rocker shaft 33 which is rigidly connected to the 130

same lever 29, which opens and closes the 5 brake through an actuating link 34. In this form the brake is obviously interlocked mechanically with the means for connecting and disconnecting the power. When lever 29 is raised to its uppermost position the brake is disconnected and the power is turned on to the motor in switch box 32, but when the lever 10 29 is pulled down to its lowest position the power is disconnected in switch box 32 and the 15 brake is applied to the inner face of brake drum 14. This prevents the possibility of the brake and power being on at the same time. The latter would be undesirable for obvious reasons.

As previously described, all the foregoing equipment is standard, and is well known in the industries, and for that reason has been 20 illustrated in the drawings only diagrammatically, in order to show the coaction and connection of the applicant's automatic equipment with the foregoing standard equipment.

Before describing this new automatic 25 equipment it will be helpful to review the present mode of manually operating the foregoing standard centrifugal, as this will aid in better understanding the features and advantages of the automatic equipment subsequently referred to.

For this description the operation in a sugar refinery will be used, it being understood that the operation in other industries is 30 modified to suit the requirements of those industries.

In a sugar refinery the operator loads into basket 1 the material to be centrifuged. He then starts the machine spinning by connecting the driving means with the power supply. 40 He does this in the belt driven type, Fig. 6, by turning handwheel 27 in the correct direction, which through rocker shaft 25, pinion 26, sector 21, and shifting pin 24, throws clutch member 19 so as to operatively connect the constantly rotating power shaft 18 with loose pulley 15, which begins to turn and by aid of belt 16 commences to turn the centrifugal. With the direct connected drive, Fig. 7, the operator accomplishes the same 45 result by raising lever 29 to its uppermost position which closes the switch in switch box 32, thereby applying the power from the electric power circuit 31 to driving motor 30, and the motor and centrifugal then begin to turn. The centrifugal comes to full speed rapidly, and the liquor component of the material in the basket is spun out under the action of centrifugal force, through the 50 foraminous cylindrical wall of the basket, and is caught and collected by the stationary curbing 4. This liquor drains out of the curbing through spout 5, and the gate 6 directs the first liquor that comes off into trough 8. After the operator has allowed this spinning 55 operation to proceed for a given period of

time, which he measures or judges by his instincts, and which presumably is sufficiently long to allow all the free liquor in the material to spin out, he then starts the automatic washer in operation by turning starting lever 12 to its going position. Water then commences to flow through this washing equipment, and is sprayed onto the material in the basket by an oscillating spray as previously indicated. This spray moves up and 70 down between the limits 13^a and 13^b, so as to uniformly distribute the wash water over the material in the basket. The automatic washer automatically measures the amount of water, and after the fixed amount is dispensed the washer automatically cuts itself out of action, terminates the flow of water, and the handle 12 retrieves to its original position, all this being accomplished without any effort or attention from the operator, except that it was originally necessary 80 for him to have started the washing operation by throwing lever 12, as described. The wash water of course penetrates the material in the rapidly revolving basket, washes 85 same, and incidentally dissolves and absorbs a portion of the material, this wash water being finally spun out under the action of centrifugal force through the foraminous cylindrical wall of the basket and being collected by curbing 4, the same as the original liquor that preceded it. This wash water however is often richer than the original liquor, and for that reason it is desired to 90 keep it separate from the original liquor. 95 For this reason the operator, either at the time of starting the washer going, or shortly thereafter, throws gate 6 so that this gate discharges into trough 9 instead of trough 8. The wash liquor then drains out of the 100 curbing through spout 5, onto the gate and is collected in trough 9, thereby effecting its separation from the original liquor, which is collected in trough 8, as previously described. After the washing operation is completed the 105 operator allows the centrifugal to continue spinning for a given period of time during which the last traces of moisture and wash water are spun out of the basket in order to 110 dry the solid material which remains in the 115 basket, having been unable to pass out because of the fineness of the openings through the foraminous cylindrical wall of the basket. This material should be dried by this 120 centrifugal drying action to a degree where its dryness is the greatest possible, short of solidifying or caking the solid material in the basket. It must not solidify because it would then be excessively difficult to discharge it from the basket. In other words, 125 the last mentioned interval of time is instinctively measured by the operator to the point where the maximum possible dryness of the material is reached, short of solidifying same. When this period or interval elapses the op- 130

erator disconnects the centrifugal driving means from the power supply, by actuating handwheel 27, Fig. 6, or lowering lever 29, Fig. 7, and he then applies the brake, by drawing lever 29, Figs. 6 and 7, to its lowest position. The centrifugal then comes to rest, and the operator discharges the solid material collected in the basket. Usually this discharging operation is performed by a hand actuated machine bolted to the top of curbing 4 and adapted to plow the sugar out of the basket 1, while same is rotating slowly. Such hand actuated machines are called dischargers. They are very common and well known in the industry, and are not illustrated in the drawings because this invention has no direct connection with the physical parts of the discharger. I wish to point out, however, that during the discharging operation it is necessary to rotate the basket slowly, which is accomplished by skillfully manipulating handwheel 27 so as to allow the clutch to slip considerably in order that the centrifugal turns slowly to permit the discharging, and yet with no tendency to bring the centrifugal to a high speed because the latter would render the discharging operation very dangerous. Even when the material is discharged by hand, instead of with a mechanical discharger, it is necessary to turn the centrifugal slowly under power in order to make the discharging operation both safe and possible. The important point to notice is that this slow speed required by the centrifugal during discharging, makes it necessary for the operator to more or less continually manipulate his power control means in order to keep the centrifugal turning and yet prevent its racing. This is particularly referred to because it has an important bearing on one part of my invention described below. When the material is discharged from the basket in the manner indicated, the centrifugal cycle is completed, and the operator is ready to start the machine on its next cycle, which he does by recharging the basket, and the above sequence of operations is repeated.

To summarize briefly the foregoing operation, and to point out more clearly its connection with the automatic equipment about to be described, it will be noticed that after the operator has charged and started his machine he relies upon his instincts for timing off a given period of time, after which he starts the automatic washer by pushing lever 12, and he also shifts gate 6 from trough 8 to 9; he then further relies on his instincts for timing off an additional given period of time after which he turns off the power and applies the brake by manually actuating handwheel 27 and brake lever 29, Fig. 6, or lever 29 only, Fig. 7.

It is these steps of starting the washer and throwing the gate after one period of time, and of turning off the power and applying

the brake after another period of time, that my invention performs automatically in a very successful manner that has several distinctive features of invention which will now be described.

My automatic equipment consists principally of the following parts, to wit: Some appropriate form of timing mechanism or time control mechanism; also some appropriate mechanisms connected with said time control mechanism and adapted to start the washing operation, to throw the gate, to disconnect the power, and to apply the brake.

In addition to the general coaction of these parts with each other and with the centrifugal mechanism, several of these parts contain distinctive subject matter of invention which may be advantageously used in connection with totally different forms or types of the other parts.

My time control means, or timing mechanism, shown in this application uses the following principle for measuring time. If water is allowed to flow under constant pressure through a given orifice a fixed amount will always be discharged in the same period of time, or conversely the amount discharged will always be in direct proportion to the time.

I therefore provide some means for maintaining water or other fluid under a constant pressure; also an orifice through which the water may flow; also a timing reservoir into which the water flows from the orifice; and finally means that becomes actuated by the water when the latter fills the timing reservoir to the particular amount for which it is set.

In Fig. 6, I show one form of means for supplying water under a constant pressure, this means consisting of a tank 35, to which water is supplied through pipe 36 and float valve 37, which is actuated in the usual manner to maintain a constant water level 38 in the tank. From this tank pipe 39 leads the water to the orifice fitting 40, from which the water passes into timing reservoir 41. The details of this orifice fitting are best shown in Fig. 5, aided by Figs. 1 and 2. This fitting has an adjustable needle valve 42 entering the bottom of a flow plug 43. The object of this is to permit the area of the orifice to be changed so as to vary the rate at which the water flows through it. The flow plug 43 has a vertical port 44 and a horizontal port 45, see Fig. 1, causing the water to enter timing reservoir 41 in a horizontal jet. I prefer to make the flow plug 43 and needle valve 42 of some very hard non-corrosive metal such as Monel metal which insures against variations in the area of the orifice through rust or corrosion, or through the reaming action of the water that passes through it. However, even with the best of materials some wear of this character will eventually occur, but this

can be compensated for by adjusting the needle valve 42, by means of the valve handle 46.

In the above arrangement the pressure of the water from tank 35 through the orifice in the flow plug 43 will be constant, and therefore under the above described principle the water will fill up the timing reservoir 41 at a rate almost directly proportionate to the time of flow through the orifice.

This timing reservoir could be arranged in various ways for indicating the instant at which it is filled with water to a predetermined place or amount, and to actuate some auxiliary mechanism at that instant for controlling the above described centrifugal operations, but I have illustrated my preferred form of timing reservoir and auxiliary mechanism in Figs. 1 to 6 inclusive, as same has some advantages which I desire to point out.

For instance, of the various means that could be used to indicate when the water has entered the reservoir to a predetermined amount, and to be actuated at that time, I prefer to use floats, and more particularly floats of the type indicated at 47 and 48, Figs. 1 and 2. These floats may be described as inverted cups open at the bottom and fitting quite closely within the walls of the reservoir 41, the floats being guided and held central in the reservoir by little guiding projections 49 cast integrally with the float. It is advisable to cast the floats in one piece out of aluminum for lightness. Such inverted cup shaped floats cannot become water soaked or filled with trapped water through leakage and thereby lose their buoyancy. As the water rises in the reservoir and reaches the bottom open edge 50 of the floats, the water traps the air inside the float, which prevents the further rise of the water within the float and obliges it to rise through the restricted space 51 between the outside of the float and the inside of the reservoir 41. The restricting of this space 51 has the benefit of making the float sensitive and quickly responsive to the presence of the water level. This is due to the fact that though the water level might have been rising quite slowly in the reservoir below the lower edge 50 of the floats, nevertheless when the water level reaches edge 50, it sweeps upward very rapidly throughout the height 52 of the float, this greatly accelerated ascent of the water level being due to the fact that the total area of space 51 around the float body is very small compared with the total area of the reservoir at places above and below the float. In other words, from the time that the water level reaches the lower edge 50, both of floats 47 and 48, to the time when these floats are completely submerged in water, and thereby actuated by their buoyancy, is very brief, especially when compared with the slow rate at which the

water level is rising at places above and below said floats, or between them, and this of course results in the floats responding promptly and sensitively to the fact that the water level has reached their lower edge 50.

Obviously when the float becomes submerged it is actuated or lifted by its buoyancy, and it is this action in the float controlled types of my reservoir which I use for in some way actuating or controlling the mechanism located at the centrifugal for opening the washer, throwing the gate, cutting off the power and applying the brake.

In considering the various means that could be employed for controlling or performing these operations at the centrifugal by the force set up through the buoyancy of the floats, various arrangements could obviously be devised. In the first place the timing reservoir could be located very close to the centrifugal, and the buoyant impulse of the floats could be directly imparted through push rods, levers, etc. to operate the required parts of the centrifugal. Also the timing reservoir could be remotely located from the centrifugal and the buoyant action of the floats could be utilized to close electrical relay circuits which could in turn be utilized in very simple manner for controlling the required operations at the centrifugal. In addition, other modes of connection between the timing reservoir and the centrifugal will readily suggest themselves, but out of the various possible mechanisms I prefer to impart the buoyant force of the floats to supplementary valves 53 and 53', see Figs. 1, 3, 4 and 6, through which, when opened, a suitable pressure medium, such as compressed air or water, oil, or other medium under pressure can be supplied through pipe connections to cylinders 54, 55, 56, and 57, Fig. 6, for respectively actuating the washer, gate, power control means, and brake, and when closed the pressure medium will automatically be exhausted from said cylinders through said supplementary valves 53 or 53'. In the electrically driven centrifugal shown in Fig. 7, the cylinders 54 and 55 for starting the washer and throwing the gate, are identical with the corresponding cylinders shown in Fig. 6, but the one cylinder 58, Fig. 7, is sufficient to both disconnect the power and apply the brake. This is because the switch box 32 and the brake is mechanically interlocked through lever 29, as previously described, and on this account the one cylinder 58 in Fig. 7, takes the place of the two cylinders 56 and 57 in Fig. 6.

The construction of the supplementary valves 53 and 53', and their connection with floats 47 and 48 is best illustrated in Figs. 1, 2, 3 and 4. These valves consist of a valve body 59 having an inlet opening 60, an outlet opening 61, an exhaust port 62, and an upwardly facing valve seat 63 located between

the inlet and outlet openings 60 and 61, and a downwardly facing valve seat 64 located between the outlet and exhaust openings 61 and 62. In this valve body there is a vertically moving stem consisting of an upper part 65, a lower part 66, and a rod or pin 67 joining parts 65 and 66 in such manner that they move and operate as a unit. The top portion 68 of stem part 65 fits nicely in the vertical hole 69 through the valve body, and likewise the lower part 70 of stem part 66 fits nicely in the similar hole 69' in the valve body, the idea being that these parts 68 and 70 of the valve stem should nicely guide the stem up and down in hole 69 of the valve body. The bottom contour of stem part 65 and the upper contour of stem part 66 is suitably beveled to seat accurately on the corresponding valve seats 63 and 64, so as to prevent the passage of the pressure medium, compressed air, water, etc., passed these valve seats, except when open. The length of the valve stem between these valve faces 71 and 72 is slightly larger than the distance between the corresponding valve seats 63 and 64 of the valve body, and this permits the valve stem to have a certain amount of vertical motion within the valve body. When the valve stem is pushed upward, valve face 72 seats against the seat 64. In this position the pressure medium supplied through the valve inlet opening 60 passes freely through the valve and out through the outlet opening 61. The right hand valve in Fig. 4 is shown in this position, and in order to distinguish this valve from the left hand one, the former is designated as 53', whereas the latter retains its designation as 53. When the valve stem however is allowed to drop under its own weight, valve face 71 closes onto valve seat 63, thereby closing the valve at this point, but opening it between seat 64 and face 72. At this time the inlet opening 60 is cut off from outlet opening 61, but the latter is open to give free passage to and through the exhaust opening 62. The left hand valve 53 in Fig. 4 is shown in the position just described. The means by which floats 47 and 48 are connected to raise and lower the valve stems will now be described.

Float 47 is connected with a push rod 73 which runs right up through the center of the cylindrical reservoir 41, and through a shroud or apron 74 which is cast as an integral part of the upper float 48. The push rod 73 is small enough to easily clear the opening through shroud 74 of the upper float, and therefore this rod can move up and down with the lower float without in any way touching or affecting the upper float. At a place above the reservoir tank 41 the central push rod 73 is connected to a ferrule member 75, Figs. 1 and 3, the latter view showing this member best. There are two pins 76 projecting a short distance radially from this ferrule, and

these pins serve to connect the forked lever 77 to ferrule 75, and since the latter is securely fastened to push rod 73 by means of set screw 78, the lever 77 is in effect connected with the push rod 73 by the swivel connection afforded by pins 76. The lever 77 in its turn is pivotally supported or hung on pin 79, and at its outer end is counterweighted by an enlarged portion 80 which is sufficiently heavy to almost, but not quite, counterbalance the push rod 73 and float 47. A set screw 81 is mounted on the head casting 82 and is set down fairly close to lever 77 as indicated in Fig. 4. From this description it will be apparent that when there is no water in the timing reservoir, or if there is water therein but in insufficient amount to submerge the lower float 47, then this float and push rod will drop of their own weight and pull the inner leg of lever 77 downward until the outer leg butts against the bottom of set screw 81 and is arrested thereby. At this time there will be clearance between the pushing face 83 of lever 77 and the bottom of the valve stem, this clearance being indicated best on the opposite lever 84, Fig. 4 which will be described presently. When the push rod 73 is raised however, as occurs when its float 47 is submerged, the inner leg of lever 77 is raised by the buoyant force of the float, and the pushing face 83 pushes on the bottom of the valve stem and raises the latter until the valve face 72 closes against the seat 64, Fig. 4. In other words, the raising and lowering of float 47 by the rise and fall of the water level opens and closes the valve 53' as will be clearly understood in connection with the previous description of the valve construction.

Just as the lower float 47 is connected with the valve 53', so the upper float 48 is connected with the opposite valve 53, the shape of the connecting parts however being slightly different. The upper float has two push rods 85, Figs. 2, 3 and 4, and these push rods are embraced at a place above the timing reservoir by a forked ferrule 86 having the yoke 87. This ferrule can be locked to the push rods 85 by means of set screws 88, Figs. 3 and 4, and from the inner portion of this ferrule 86 project two pins 89, which pivotally connect the swivel to the forked lever 84, the same as the previously described pins 76, Fig. 3, connect ferrule 75 to lever 77. Lever 84 is pivotally carried by pin 90, has a valve pushing face 91, is limited in its movement one way by set screw 92, and has an enlarged counterweight portion 93 as its outer extremity, the functions and purposes of all of which are identical with the corresponding features of the opposite lever 77 as previously described, and from the foregoing construction it will be understood that the upper float 48 therefore controls the left hand valve 53, Figs. 1, 3 and 4, the same as the lower float 47 controls the right hand valve 53'.

The means for gradually filling the timing reservoir 41 with water having been previously described, I will now describe the means for rapidly emptying the water out of this reservoir at the end of the cycle. This emptying means primarily consists of a large valve located at the bottom of the timing reservoir, this valve being best illustrated in Figs. 2 and 5. It consists of the valve seat 94 against which fits the heavy rubber packer 95 which is carried between the head 96 and the heavy lead weight 97, this weight having the cap screw 98 embedded therein for the purpose of fastening the weight to head 96. The rod 99 is fastened to head 96 by means of a pin 100 and a cup leather 101 is fastened to the lower part of rod 99 in the usual manner to form a leak-proof piston operating in the cylinder 102. Near the centrifugal, and at a position that can be conveniently reached by the operator, there is a three-way valve 103, Fig. 6, having the three ports 104, 105, and 106, and the central valve core or stem 107 having the port 108. When this valve is set in the position shown in Fig. 6 a pressure medium comprising air, water or other fluid under pressure is supplied from the line 109 through this valve to line 110 which connects into the bottom of cylinder 102 below piston 101, and this pressure medium raises this piston and all the parts connected therewith, including packer 95 off the valve seat 94, thereby emptying the water out of the reservoir 41. This water passes out through the large pipe connection 111 from whence it may be discharged either into the sewer or into some suitable pumping arrangement to again lead it into the supply tank 35 Fig. 6, to be used over and over again. It is not necessary to show the latter connections as they are optional with the user of this control equipment. As long as the valve 103 remains in its position shown in Fig. 6, the pressure medium will hold the cup leather piston 101, rod 99, packer 95 and the other connected parts, in their uppermost position, i. e., packer 95 will be lifted off seat 94, and the water which continues to enter the timing reservoir 41 from tank 35 through flow plug 43 will not collect in the reservoir but will immediately and continuously pass out between packer 95 and seat 94 so long as the latter are held apart. However when the operator at the centrifugal desires to start the timing action in the reservoir, i. e., when he desires the water to collect and rise in the reservoir instead of discharging through pipe 111, as he does desire to do when he starts the centrifugal on its next cycle after having charged same and started it spinning, he simply turns the valve handle 112, of valve 103, indicated diagrammatically in Fig. 6, 90° to the right in direction of arrow "a" which causes valve port 108 to establish communication between ports 105 and 106, the latter being an exhaust port as previously described, and this therefore causes the pressure medium to be immediately exhausted from cylinder 102 out through exhaust port 106, and under the action of weight 97, the valve packer 95 drops quickly onto valve seat 94 closing the opening at that point and thereafter causing the water that enters through the flow plug to collect and rise in the timing reservoir 41, instead of discharging into the discharge pipe 111 as it was previously doing. From the foregoing description it is of course understood that as the water level rises in the timing reservoir, it presently reaches and rapidly sweeps over the lower float 47, thereby lifting same a small amount to actuate valve 53' as previously described, after which the water level continues to rise slowly above this float until it reaches and rapidly sweeps over the upper float 48 and thereby lifts same a small amount to actuate valve 53, as previously described. In Figs. 1 and 2 the timing operation is in progress, the water level having already reached position 113 in its upward course. At this time the lower float 47 will have been lifted by its buoyancy, but the upper float 48 will still be at its normal lowermost position as limited by set screw 92. When the water level presently reaches this upper float it will be raised a small amount, like float 47 had previously been, the upward motion of both floats being limited as the valve faces 72 butt against their seats 64 in valves 53 and 53'. Obviously the time that elapsed from the instant when the operator threw the valve handle 112 to the position that drops the packer 95 onto seat 94, to the time when the lower float and valve 53' are actuated by the rising water level, and likewise the time elapsing from this instant to the instant when the upper float and its valve 53 are actuated by the rising water level, depends upon the respective heights of float 47 and 48 in the timing reservoir and these intervals will always remain the same as long as these heights remain the same, and as long as the water pressure entering flow plug 43 remains constant. Sometimes however it is necessary to change the length of these time intervals, and this can be done by raising or lowering either or both floats to any desired height or position in the timing reservoir. The height of float 47 can be changed by loosening set screw 78 and by raising or lowering push rod 73 which carries float 47, and which will pass freely up or down through ferrule 75 until float 47 is in its new desired position at which place it can be secured by refastening set screw 78. Likewise the height of float 48 can be changed by loosening set screws 88 and by raising or lowering push rods 85, which carry float 48, and which will freely pass up or down through ferrule 86 when the set screws are loose, and when float 48 is in its new desired position it can be fixed there by again fastening the set screws 88. It is by means of

the adjustment of the float heights as just indicated, that the time intervals for controlling the centrifugal operations can be changed and adjusted when the character of material 5 on which the centrifugal is working requires such change. In Figs. 1 and 2 I have shown the index plate 113³ mounted on the head casting 113², and this plate can be graduated as indicated in Fig. 2 so that by reading or sight- 10 ing across the top end of push rod 73 onto these graduations, and by sighting across the lower edge 113³ of yoke 113⁴, against the graduations, the above described time intervals for any particular float setting can be read direct- 15 ly in minutes and seconds. It is obvious that the upper edge of push rod 73 gives the position of the lower float 47 and the lower edge 113³ of the yoke gives the setting of the upper float 48. The yoke 113⁴ is fastened to the push rods 85 20 at their upper extremity. The use of such an index plate calibrated either directly in minutes and seconds or else calibrated in inches to give the exact height of the floats in the reservoir, is found very convenient in practice as a 25 means of accurately changing the time intervals at which the floats are actuated.

In regard to the manner in which the compressed air or other pressure medium is supplied to the valves 53 and 53', Fig. 6 shows that 30 from the supply line 109 previously described, a branch pipe 114 leads the pressure medium to the inlet connection 60' which enters the inlet ports or openings 60 of both valves 53 and 53'. When the valve stems in these valves 35 are in their lowermost position, as is the case when the floats are not buoyed up against them, the valves of course close off the pressure medium so that the latter cannot get beyond the valves. As the floats however are 40 respectively raised to lift the valve stems, the compressed air, or other pressure medium is released through valves 53' and 53 into suitable connections that lead respectively to the washer and gate throwing mechanism from 45 valve 53' and to the power control and brake mechanism from valve 53. At these terminal points the compressed air, or other pressure medium, could be utilized in various ways to start the washer, throw the gutter, 50 disconnect the driving means from the power supply and apply the brake. One of the most obvious modes of actuating these parts would be to have a weight or spring controlled mechanism which tends to normally push each of 55 these parts, particularly the power control and brake mechanism, in the direction in which the man would push them when the time for actuating these parts is reached. The constant pushing tendency of these weights 60 or spring controlled mechanisms could normally be arrested by simple latch mechanisms until the time is reached for the weights or springs to function in actuating their respective parts, and small cylinders, or other suitable devices, could then be used to pull out 65

the latches and permit the weight or spring controlled members to function when the compressed air from valves 53 and 53' is supplied to them. There are several objections however to such weight or spring controlled mechanisms, particularly in regard to their use in conjunction with the power control and brake mechanism. In a general way the nature of these objections becomes apparent in connection with the previous remarks which I have made regarding the necessity of the operator continually manipulating the power control and brake mechanism during the discharging of the centrifugal. In this period he constantly manipulates the handwheel 27, Fig. 6, or control lever 29, Fig. 7, back and forth in order to connect with the power source to start and keep the centrifugal turning slowly for discharging, but he promptly disconnects from the power source as soon as 70 the centrifugal speed rises because rapid rotation makes discharging dangerous. This continual manipulation of the power control and brake mechanism during discharging is fairly difficult and requires some skill by the operator. The addition therefore of spring or weight controlled mechanisms which would constantly tend to throw the power on and the brake off, except when the operator threw the power control and brake lever far enough over 75 to catch them in the latch, would still further complicate the already difficult operations of the operator during the discharging period. In the first place the force of the springs or weights must be considerable in order to 80 promptly actuate the power control and brake mechanism when the time for such actuation normally arrives, but during the discharging operation the operator would be obliged to push more vigorously on the power control 85 in order to overcome the added spring or weight pressure, and this added exertion would make his work more difficult at a period when increased difficulties are extremely undesirable because of the dangerous character of discharging. Likewise if he accidentally happened to throw the power control or brake mechanism so far, during the discharging operation, that they caught in the latch, he 90 could not pull back either the power control or brake without first releasing the latch, and to impose this possible burden on him would be very undesirable because of the damage that might be done to the discharging equipment through high speed reached before the power could be cut off and the brake applied. I have found however that all of these objections can be very easily and perfectly overcome by use of cylinders generally of the type of those shown at 56 and 57, Fig. 6, and 58, Fig. 7, these cylinders being connected directly to the power control and brake mechanism for actuating the latter. When compressed air, or other pressure medium is applied to cylinder 56, it operates through crank 56^a to 95 100 105 110 115 120 125 130

turn shaft 25 in the same direction that the operator would have done if he grasped and turned handwheel 27 in the usual way for disconnecting from the power by disengaging the 5 clutch mechanism. Also when compressed air is supplied to cylinder 57, Fig. 6, this cylinder pushes down brake lever 29 in the same direction and manner that the man does when he applies the brake. Also, when compressed 10 air, or other pressure medium, is supplied to cylinder 58, Fig. 7, it pushes down the lever 29 which is in this figure simultaneously serves to disconnect the power in switchbox 32 and to apply the brake as previously described. 15 However the instant that the compressed air, or other pressure medium, is released from these cylinders 56, 57 and 58, they immediately become inert or neutral, by which I mean that they do not continue to push their 20 respective members in the direction that they do when the air is applied. In fact when the compressed air is off, these cylinders exert no influence whatever upon their connected members, and this is much better than the above 25 proposed spring or weight controlled attachments because the latter are constantly pressing forward on their connected members except when the latter has been thrown over far enough to engage a latch. By using cylinders 30 in the manner that I have shown for disengaging the power and applying the brake, the work of the operator during the discharging operation is in no wise increased or rendered more complicated than it was before this 35 automatic equipment was installed, the reason obviously being that during the discharging operation the compressed air is off the cylinders 56, 57 and 58, and these cylinders are therefore dragged back and forth when the 40 connected parts are manipulated, with no resistive force except the extremely small amount of friction in the cylinders and this is so little that the operator neither notices nor minds it. In Fig. 6, even though I have 45 shown cylinder 56 connected to shaft 25 through crank 56^a, as the means for disengaging the clutch, nevertheless it is obvious that this cylinder 56 may be connected to other parts of the power control mechanism for the 50 purpose of disconnecting the driving pulley 15 from the power source which consists in the constantly rotating power shaft in Fig. 6. To summarize, the important feature which I have tried to point out in the foregoing description regarding cylinders 56, 57 and 58, is that they are connected directly to the power and brake control means, and that they 55 actuate the latter directly, instead of merely pulling out latches to release weight or spring controlled mechanisms which actuate the power and brake control members. Of course if the designer or user of this automatic equipment desires to use the force of compressed air, or other pressure medium, or electrical impulses, to pull out such latches for releasing 60

weight or spring controlled mechanisms, to actuate the power and brake controlled mechanisms, the same can be done in connection with the features of invention embodied in my previously described timing reservoir, but 70 I do not consider this as practical a form of disengaging means as the direct use of the cylinders in the manner above described. The latter arrangement is very efficient and has many advantages not possessed by other forms 75 of automatic power disengaging means.

In the same manner that I use cylinders 56, 57 and 58 for disconnecting the power and applying the brake, I have also found it 80 advantageous to use cylinder 54 connected with washer control handle 12 for starting the washer, and cylinder 55 connected with gutter 6 for throwing this gutter from trough 8 to trough 9. Normally the counterweight 55^a, Figs. 6 and 7, directs gutter 6 into trough 8, but the upward movement in cylinder 55 85 throws the gutter over to trough 9 in an obvious manner.

Each of the cylinders 54, 55, 56, 57 and 58 90 respectively have the following parts, to wit: suitable packers or pistons preferably consisting of cup leathers 54', 55', 56', 57', and 58'; also piston rods 54², 55², 56², 57², and 58²; and also supporting pins 54³, 55³, 56³, 57³ and 58³. Each of the piston rods for these 95 various cylinders is respectively connected to the part which it actuates, as is obvious from Figs. 6 and 7, and also the supporting pins just described fit loosely in each of the cylinders in such manner as to permit the cylinders to rock and humor themselves on these 100 pins to permit the angular movement imposed on the cylinders as the connected parts swing on their respective pivots. Of course these supporting pins are in their turn each 105 supported by some suitable structure, but the latter has been omitted from the figures for purposes of clearness, and an average mechanic will have no trouble whatever in arranging suitable supporting structure for 110 these pins under the various circumstances and conditions for installation as found in the places where this automatic equipment may be used.

By reference to Fig. 6 it is seen that the 115 valve 53' has its outlet connection 61' leading from outlet opening 61, connected through pipe 115 to washer cylinder 54, and through a branch pipe 116 to the gate control cylinder 55. Likewise valve 53 has its outlet connection 61' leading from outlet opening 61, connected through pipe 117 to cylinder 56, and if desired, the dotted line branch 118, Fig. 6, can connect pipe 117 with pipe 119 120 leading into cylinder 57. Therefore when the valve stem in valve 53' is raised by the lower float 47, then in view of the previously described valve construction, the compressed air or other pressure medium passes from the 125 supply connection 60' through the valve 53' 130

and through pipes 115 and 116 respectively into cylinders 54 and 55 to respectively open the washer handle 12 for starting the washing action just as the man would have done, 5 and also to shift the gate 6 from trough 8 into trough 9, as the man would have done by hand. These operations are accomplished when the timing mechanism reaches the place where the valve stem is pushed upward in 10 valve 53', as previously described. Likewise when the valve stem in valve 53 is raised by the upper float 48, then the pressure medium passes from supply connection 60' through valve 53 and through pipes 117, 118 and 119 15 into cylinders 56 and 57 which respectively disconnect the centrifugal driving means from the power source, and apply the brake as previously described. It is also understood that these latter operations for bringing the 20 centrifugal to rest are automatically accomplished when the timing mechanism reaches the place where the valve 53 is actuated in this manner.

If the dotted line connection 118 joining 25 pipes 117 and 119 is used,—see Fig. 6,—, then cylinders 56 and 57 are actuated simultaneously, but this has a certain disadvantage because of the fact that the adjustment of the clutch mechanism and the adjustment of 30 the brake mechanism may sometimes be such that simultaneous action of cylinders 56 and 57 might actually result in a brief period when the clutch is not actually disengaged at the time that the brake is applied, and when 35 this occurs it is obvious that the brake would be fighting against the clutch and power for the short period during which both the brake and the clutch are on. This of course is detrimental not only to the clutch and brake, 40 but to the belt as well, and should be avoided if possible. For the purpose of avoiding this undesirable condition I therefore prefer to omit entirely the dotted line connection 118, and instead to connect pipe 119 into the lower 45 end of cylinder 56 at such a place that the pressure medium from pipe 117 only enters cylinder 56 for the purpose of pushing its piston downward to cut off the clutch. During 50 almost the entire amount of this piston movement, and corresponding disengaging movement of the clutch, the pressure medium has no means of entering pipe 119 and cylinder 57. However, when piston 56' in cylinder 56 reaches almost the end of its stroke, which 55 is so adjusted that the clutch is surely disengaged at this point, then this piston 56' opens communication from the upper compression chamber in cylinder 56 to the full line pipe connection 119 entering the lower 60 part of cylinder 56 and permits the compressed air to flow from pipe 117 through cylinder 56 into pipe 119 and cylinder 57 to 65 actuate the latter and throw on the brake. With this arrangement it is obvious that cylinders 56 and 57 are not actuated simul-

taneously, and therefore that the clutch mechanism and brake are not disengaged and applied simultaneously; but on the contrary the clutch mechanism is first completely disengaged by the action of cylinder 56 through 70 almost its entire stroke, before the brake commences to be applied by the admission of the pressure medium to pipe 119 and cylinder 57. It will of course be understood that when dotted line connection 118 is used, then the 75 full line connection of pipe 119 into the bottom of cylinder 56 is omitted, and conversely when the latter full line connection into cylinder 56 is used, then the dotted line connection 118 is omitted. 80

In the direct connected electric driven centrifugal shown in Fig. 7 the pipe connection 117 leading from valve 53 is connected directly into cylinder 58, which is the only cylinder used in this form of the invention. This 85 one cylinder 58 serves the double purpose of disconnecting the power in switchbox 32, and of applying the brake, this being possible because the power control in the switch-box and the brake are mechanically interlocked by 90 means of the shifter shaft 33, shown in Figs. 7 and 8.

In order to permit cylinders 54, 55, 56, 57 and 58 to rock and oscillate freely on their respective supporting pins 54³, 55³, 56³, 57³ and 58³, it is necessary that either the entire pipe lines respectively leading to these cylinders, to wit: pipe lines 115, 116, 117 and 119, Figs. 6 and 7, should be made of flexible tubing or rubber hose, or else the last portion 95 of these lines for approximately a foot or so at the end where they enter the cylinders should be of flexible tubing or rubber hose, and the balance can then be rigid metallic pipe or tubing. The use of the flexible tubing at the immediate entrance to the cylinder permits the latter as indicated, to rock on their supporting pins in order that the cylinders can accommodate themselves to the 100 swinging motion imposed on them by the various levers, crank etc. to which they are connected. 105

With the exception of a few details this now concludes the description of the invention.

In operating same the procedure is as follows: While the operator is loading a charge of material into basket 1 of the centrifugal, at the beginning of the cycle, valve 103, which is conveniently located for the operator near the centrifugal, is in the position shown 115 in Fig. 6, wherein the compressed air passes from supply line 109 through valve 103 and pipe 110 into cylinder 102 at the bottom of the timing reservoir 41. As previously described, the action of the pressure medium in 120 this cylinder 102 holds packer 95 off its seat 94 in the timing reservoir and permits the water which is constantly entering the timing reservoir from the constant level tank 35 through the flow plug 43 at a constant rate 125 130

of speed, to pass right out from the timing reservoir under packer 95 into discharge pipe 111, instead of collecting in the timing reservoir for the purpose of measuring time which is the function of the water that is so flowing. When the operator has fully charged the basket he throws the power on for the purpose of bringing the centrifugal up to full speed. In the belt driven type of drive, as shown in Fig. 6, he does this by turning handwheel 27 through about 90° in the correct direction, which actuates the clutch in the usual manner in order to connect the belt drive with the constantly rotating power shaft 18. The brake is of course in its uppermost or "off" position at this time. In the electric driven centrifugal the operator starts the machine turning to full speed by raising lever 29 to its uppermost position which automatically disengages the brake and connects up with the power source in switchbox 32. As soon as the operator has thrown on the power in the manner just described, he considers the cycle as commencing, and he immediately turns lever 112 of valve 103 through approximately 90° to the right, as indicated by arrow "a", and in accordance with the usual principles of three-way valves this cuts off communication with supply line 109 and opens communication from pipe 110 to exhaust port 106, allowing the pressure medium in cylinder 102 to be immediately released into the air through exhaust port 106 and under the action of weight 97 in the timing reservoir 41, packer 95 is immediately pushed down onto seat 94, thereby closing off the outlet from the bottom of the timing reservoir and causing the water, or any other equivalent medium that may be used instead, to accumulate and rise in the timing reservoir as previously described. During this time, and until the floats are submerged by the rising water, both valves 53 and 53', Fig. 4, are in the position shown for the left hand valve 53 in this figure, i. e., the valve stem is in its lowest position with the valve face 71 down on valve seat 63 so as to shut off the connection from supply line 60' which furnishes the pressure medium, or in other words the pressure medium cannot get beyond valves 53 and 53', and the cylinders 54, 55, 56, 57 and 58 are entirely inert and without energy. However as the water level in the timing reservoir rises and finally submerges the lower float 47, the buoyancy of the float pushes upward the valve stem in valve 53', this action being transmitted through push rod 73 and lever 77, as previously described. The right hand valve 53', Fig. 4, is shown raised in this manner, and it will be noted that the upper valve face 71 is off its seat 63, while the lower valve face 72 is pressed up against its seat 64. In this position communication exists between the supply line 60' and the outlet connection 61', thereby

admitting the pressure medium to the washer cylinder 54 and the gate cylinder 55. This starts the washer operating in exactly the same manner that it would have commenced to operate if the man had opened the washer lever 12 by hand, as was previously the custom. The washer continues to operate in its regular manner as outlined fully in the previously described Hartman patent, and after the washer has operated to the given amount of time for which it is set, it is automatically cut off by its own time controlled mechanism within the washer. When the washer was cut on, the nozzle arm 12^a which is normally at rest, immediately commences to oscillate in order to sweep the spray between the upper and lower limits 13^a and 13^b, Figs. 6 and 7, and this oscillation continues while the washer operation continues, and when the washer cuts itself off under its own time controlled mechanism, as set forth in the Hartman patent, it not only closes its own time controlled valve, but also disconnects the nozzle arm 12^a, so that the latter ceases to oscillate. Also in regard to the syrup gate 6, and gate cylinder 55, Figs. 6 and 7, it will be understood that prior to the admission of the pressure medium through valve 53' into cylinder 55, the action of the counterweight 55^a had held the syrup gate 6 in its upper position shown in full lines in the figure and directing the original syrup or liquor spun off from the material in basket 1 and collected and discharged from curbing 4 and outlet 5, into trough 8. However when cylinder 55 is energized by the pressure medium supplied through valve 53', this cylinder throws gate 6 so it directs the subsequent liquor from curbing 4 into gutter 9 instead of gutter 8. The reason for this separation of the liquors is that the portion that comes from curbing 4 after the washer has commenced to operate is frequently much richer because of having dissolved into itself a portion of the material that is being centrifuged and washed in the basket, and it may be profitable to subsequently work this liquor differently than the original liquor, due to the increased richness of the former. Of course in some industries it is not desired to separate this wash liquor from the original liquor, and in that case only one trough is used instead of the two shown, and the gate throwing cylinder 55 is omitted. On the other hand, in some industries it is desired to make the separation between the rich wash liquors and the original liquor as accurate as possible, and this is slightly complicated by the following condition. As the instant when the washing action commences, the walls of curbing 4 are still dripping with a considerable amount of the original liquor which has been spinning on to it prior to that instant, and which had not yet had time to drain out of the curbing onto gutter 6. Therefore, if the gate-throwing cylinder 55

were fully actuated at the same instant that the washer cylinder 54 is actuated to start the washing, than it might be said that the syrup gate 6 is prematurely thrown from gutter 8 to gutter 9, because the remaining original liquor that would still be draining off of curbing 4, and would continue to do so for a few moments, would drain into the rich liquor gutter 9, instead of into the original 10 gutter 8 where it belongs. In order to prevent this it may be desirable to retard the throwing of gutter 6 for a few moments after the washer is turned on in order to permit the original liquor that still clings to curbing 4, 15 to completely drain into the original liquor trough 8 before gate 6 shifts from trough 8 to trough 9 in which the rich wash liquor will then alone be gathered. One very convenient mode of retarding gate 6 in this manner is to install a finely regulated valve 116' 20 in the pipe 116 leading to cylinder 55. This valve can be throttled down to a very fine point so as to cause the pressure medium to only pass very slowly through it into cylinder 25 55, on which account the latter cylinder will only be actuated very slowly, and gate 6 will therefore pass from trough 8 to trough 9 at a time subsequent to the instant when the washer was thrown on, the amount of the 30 delay of course depending on the amount by which valve 116' is throttled down. Also if compressed air is used for the pressure medium, it might then be a little troublesome to throttle valve 116' sufficiently to appreciably retard the throwing of gate 6 after the 35 starting of the washer. If difficulty of this sort, due to the speed with which compressed air operates, is encountered, then the cylinder 55 and pipe 116 may be filled with water 40 or oil, and an enlarged chamber 116², serving as a reservoir may be installed in pipe 116, preferably above valve 116'. Enough water should be put in to fill the cylinder, pipe 116 and a substantial part of reservoir 116². 45 When the compressed air then enters chamber 116² from pipe 115, the air forces the water downward to life the piston in cylinder 55, but since no difficulty whatever will be encountered in throttling or choking down 50 the flow of water or oil through valve 116', no difficulty will be encountered in retarding the action of cylinder 55 in throwing the gate to any degree that might be required. 55 If it is desired that the gate should then drop back quickly under the action of counterweight 55^a, from trough 9 to trough 8, after the compressed air is subsequently released at the end of the cycle through valve 53', a by-pass connection 116³ with a check 60 valve 116⁴, can then be installed as shown in Fig. 6 for the purpose of by-passing around valve 116'. Check valve 116⁴ should be installed to allow the liquid to flow in direction of arrow "b", from cylinder 55 toward reservoir 116², but when flowing in the opposite

direction the check valve should close so as to force the liquid to flow from reservoir 116² to cylinder 55 only through the restriction set up by the throttle valve 116'. This results in causing the gate to move very slowly when compressed air is admitted to reservoir 116², and consequently retards the time when gate 6 actually passes from troughs 8 to 9, but causes the gate to move very rapidly in the return direction at the end of the cycle, 75 from troughs 9 to 8. This idea of causing the liquid to enter cylinder 55 very slowly by allowing it to only pass down through the restricted valve 116', but of allowing it to exhaust itself rapidly from said cylinder by 80 by-passing upward through the copious check valve 116⁴ as well as the restricted valve 116', is quite useful. It is of course understood that the water or oil so used simply surges or moves back and forth from cylinder 55 to reservoir 116², and does not exhaust itself into the outer atmosphere during operation. The compressed air which operates on the upper surface of this liquid, may 85 gradually carry away a small portion of the liquid with it due to entrainment, but the amount so dissipated is small and by occasionally replenishing the supply no trouble is encountered. Instead of the valve 116' it is feasible to use a small flow plug such as a 90 washer or small section of pipe with an extremely small hole through it. In fact any arrangement that greatly restricts the flow through it, may be used. I have proposed the valve 116' because same is adjustable, which 95 enables the operator to easily set it to give the particular retardation in the throwing of gate 6 after the washing commences, that he may desire. Of course as long as the lower float 47 in timing reservoir 41, remains submerged, so as to hold valve 53' open, the compressed air or other pressure medium will 100 hold the piston in cylinder 55 in its uppermost position, which in turn holds gate 6 in position to direct all liquor coming from curbing 4 into trough 9. This is as it should be, because after the washer is once started, and the separation from troughs 8 to 9 is 105 made, all the liquors thereafter coming from the trough during that cycle should continue to drain into trough 9, and the gate should not go back to trough 8 until the next cycle commences. 110

After the washing action has been started, and the gate thrown by the automatic action of the timing equipment as previously described, this equipment continues to measure time by the progressive rising of the water level in the timing reservoir 41, and when the particular period of time has elapsed which corresponds with the position or elevation of the upper float 48 in the timing reservoir, the water level will reach this float, submerge the same, and actuate valve 53 in the same manner as was previously described in con- 115 120 125 130

nection with valve 53'. When this occurs valve 53 will release the pressure medium and permit same to flow freely from the supply connection 60', out through the outlet connection 61' which enters pipe 117, and through same the pressure medium first enters cylinder 56, Fig. 6, to throw off the power as previously described, and then by-passes into pipe 119 and cylinder 57 to apply the 10 brake as previously described. In Fig. 7 the pressure medium enters cylinder 58 which serves the double purpose of throwing off the power and applying the brake. This operation of course results in bringing the centrifugal to rest quite shortly after the brake is applied.

In reviewing the foregoing operations it will be noticed that from the instant when the operator commenced the cycle by throwing 20 the handle 112 of valve 103, 90° to the right from its position shown in Fig. 6, so as to place the centrifugal under the action and control of the automatic equipment, there was nothing further for him to do in connection 25 with the individual operations he formerly performed by hand. He is no longer obliged to turn on the washer and throw the gate, as these operations are automatically performed for him; and likewise he is no longer required 30 to turn off the power and apply the brake, because these operations are also automatically performed for him. Therefore in place of the operator waiting at his centrifugal for the time to pass until he can respectively 35 perform these individual operations, he can now leave his centrifugal and perform other productive work, as for instance tending additional centrifugals which he did not do before. In other words, the installation 40 of this automatic equipment results in saving labor, and also in performing the above individual steps in more accurate time sequence than the operator was previously able to do when measuring time by his instincts 45 only. With this automatic equipment the operator merely charges the centrifugal as previously described, throws the valve handle 112 of valve 103 so as to put the centrifugal under the control of the automatic equipment, then goes about other work at other 50 centrifugals, and when he gets back to the one in question it is either completely stopped, or in the act of stopping for him, so that he can discharge the material from the basket, recharge same and go on with the next cycle 55 in the same manner that he did for the previous one.

As just indicated, when the operator gets back to the centrifugal he finds it at rest waiting for him to discharge it. At this time however cylinders 56 and 57 are firmly holding the power control means in its "off" position, and the brake in its "on" position, the reason for this being that the water in 65 the timing reservoir has risen above the up-

permost float, and therefore lifts same against its valve 53, which it continues to do until the water is discharged from timing reservoir 41. Therefore in order that the operator can release the brake and again apply the power for slowly turning the centrifugal to permit him to discharge the material from the centrifugal, it is necessary for him to throw lever 112, of valve 103, into the position shown in Fig. 6. The pressure medium from supply pipe 109 then enters cylinder 102 at the bottom of timing reservoir 41, and lifts packer 95 off its seat 94 as previously described, and the entire quantity of water collected in timing reservoir 41 rapidly discharges through outlet pipe 111 from the bottom of the timing reservoir, and this reservoir is emptied, or in other words reset to the original position that it was in when the cycle was started. In case the operator is slow in getting back to the centrifugal for the purpose of emptying the timing reservoir as just described, so that the water level rises to an abnormally high point in this reservoir, then the water will finally overflow through opening 121, see Fig. 2, located near the top of the timing reservoir, and from this opening it will flow down through the hose 122 and other connections shown, and discharge out through the discharge pipe 111 as is obvious from Fig. 2. This prevents the possibility of the water flowing over the top of timing reservoir 41 onto the floor.

As soon as the operator has thrown lever 112, of valve 103 into the position shown in Fig. 6, the downward rush of the water as it discharges from timing reservoir 41 immediately and vigorously pulls both floats 47 and 48 downward, and thereby releases the valves 53 and 53' from the lifting action that the floats had been previously exerting upon these valves. Under the weight of the valve stems, plus the force of the pressure medium in the valve bodies, the valve stems immediately drop down to the original position that they were in as shown in the left hand valve 53, see Fig. 4. This not only cuts off communication from the supply connection 60' to each of the cylinders 54, 55, 56, 57 and 58, but in addition permits the pressure medium within these cylinders to immediately exhaust itself by passing back through opening 61 into valves 53 and 53', and thence downward and out from the valve through the exhaust port 62 into the atmosphere, this being possible because the lower valve face 72 is at this time down off its seat 64 as is shown in the left hand valve 53 of Fig. 4.

The pressure medium being thereby released from cylinders 54 and 55, these are instantly retrieved to their original position under the respective action of spring 123 in cylinder 54, and of the counterweight 55a in cylinder 55, the latter bringing gate 6 back to trough 8 ready for the next cycle as pre- 130

viously described. Likewise, the pressure medium being thus released from cylinders 56 and 57, Fig. 6, and from cylinder 58, Fig. 7, the operator is free to release the brake by 5 pushing hand lever 29 upward, and to commence to turn the centrifugal for discharging, by means of hand manipulation of the handwheel 27 on the power control. As previously mentioned the operator discharges 10 the centrifugal, and during this period he is continually manipulating the handwheel 27 so as to keep the centrifugal turning, but without permitting it to reach a high speed which would be dangerous during the dis- 15 charging operation. While he is engaged in this work it is very helpful to him that the cylinders 56 and 57 are entirely inert, as they then in no manner exert any appreciable resistance against his manipulation of the 20 power control and brake, as would be the case if the power control and brake are actuated by spring or weight controlled expedients. On this account the use of cylinders for this purpose of throwing off the power and applying 25 the brake is exceptionally efficient and desirable, and so far as I am aware I am the first person who has used them in this connection and who has pointed out their exceptional benefits and usefulness in this particular application. I therefore consider this feature 30 of my invention of especial pioneer importance.

Before concluding this specification I would like to refer to Figs. 9, 10 and 11 which 35 show the particular manner in which the washer cylinder 54 co-acts with the washer mechanism for the purpose of starting or opening same. It will be understood from the previously mentioned Hartman patent, 40 that after once the starting lever 12 is thrown on, which opens the water valve within the washer box, and also makes engagement to start the nozzle arm 12^a oscillating, the automatic washers of that type have their own 45 time measuring equipment, and after the time for which the washer is set, elapses, the washer cuts itself off by snapping its control lever 12 back to its original position, which automatically closes the washer valve and disconnects 50 the mechanism which oscillates nozzle arm 12^a, so that the latter ceases to oscillate. However, if the washer cylinder 54 were directly and permanently connected with the washer control lever 12 in the ordinary manner, it is 55 obvious that this control lever could not snap back to shut off the washer after the time measuring equipment in the latter reached the point where such shutting off was normally accomplished. The reason is that the 60 pressure medium in cylinder 54 would continue to hold the washer lever in its "going" position, and until the water was discharged from timing reservoir 41, to permit float 47 to drop and thereby release the pressure me- 65 dium from washer cylinder 54, it would not

be possible for the latter to retrieve and permit the washer control lever to retrieve, even though the automatic features of the washer called for such retrieval. This lack of co-operation between the two mechanisms could 70 not of course be tolerated. To overcome this difficulty I have connected washer cylinder 54 to the washer in a special manner as indicated in Figs. 9, 10 and 11. In the first place I have bent the washer control handle 12 in the manner shown in these figures. The piston rod 54^a of this cylinder is equipped with a hard steel projection 124 which is adapted to butt against the horizontal projection 12' of the washer control lever as shown in Fig. 9, and 75 the piston rod 54^a is prolonged to a point where it practically overhangs the nozzle arm 12^a as shown in Figs. 9 and 10. Therefore when the pressure medium enters cylinder 54 to actuate same, the steel projection 124 pushes 80 the control lever 12 to its "on" or "going" position as indicated by dotted lines in Fig. 9 and by full lines in Fig. 10. When this occurs the outer end of the piston rod 54^a of cylinder 54 takes the position shown in dotted 85 lines in Fig. 9. Immediately the water commences to flow through the washer, and the nozzle arm 12^a commences to oscillate up and down. As this arm rises from its lowest 90 position shown in Fig. 9 to its uppermost position shown in Fig. 10, it lifts the piston rod 54^a upward, the cylinder 54 swinging on its pin 54^b for this purpose if necessary, and as 95 the rod 54^a rises it lifts the steel projection 124 sufficiently so that it slips off the top of the lever portion 12', and under the continued 100 impulse of the pressure medium in cylinder 54, the piston and steel projection 124 move forward to the position shown in Fig. 10, the motion being limited by a stop 125, Fig. 10, 105 butting against the outer overhung extremity 126 of cylinder 54 as shown. With this arrangement it is obvious, that even though the pressure medium holds piston 54^a in its outermost position as shown in Fig. 10, throughout 110 the remainder of the centrifugal cycle, nevertheless when the timing mechanism within the washer reaches the point where it snaps the control handle 12 of same into its "closed" or "off" position, there is no opposition 115 to this action set up by the washer cylinder 54, and the control lever 12 snaps back to its full line position shown in Fig. 9, even though the washer cylinder 54 and the rod 54^a remains in its extended position as shown 120 in Fig. 10. At the end of the cycle however when the pressure medium is released from this cylinder as previously described, the spring 123 in this cylinder retrieves the piston to its original position which is as far 125 or further back than the full line position shown in Fig. 9, in which position the mechanism awaits to repeat its functions in the next cycle.

Fig. 11, in addition to showing the co-ac- 130

tion between the nozzle arm 12^a and the piston rod 54² for lifting the latter, also shows diagrammatically the internal connections within the washer box whereby the shaft 128 which is rigidly connected to control lever 12, opens and closes the water valve 129 within the washer box. These connections essentially consist of arm 130 on shaft 128, loose link 131, bell crank 132, and valve stem 133 which enters the valve and actuates same in the usual manner. When control lever 12 is thrown one way it pushes valve stem 133 upward to open the valve; and when the control lever 12 is thrown the other way it draws valve stem 133 downward to close the valve. The other automatic mechanism within the washer 10 whereby the time during which valve 129 is kept open, and at the end of which it is automatically closed so as to make this valve a time controlled valve, and also the automatic mechanism within this washer whereby the nozzle arm 12^a is started and stopped oscillating when control handle 12 is thrown "on" and automatically "off", need not be shown in the drawings, as all these details are fully covered by referring to the above mentioned Hartman patent, the construction and use of which is well known and general throughout the industry particularly on the subject of this Hartman washer measuring the quantity of water by means of the time controlled valve within it. In Fig. 11 water enters this washer from a constant level tank not shown in the drawings, through pipe connection 11, from which it passes through valve 129 when open, into fitting 135, and thence through flexible hose 136 into the rear end of nozzle arm 12^a, as indicated in Fig. 11. The flexible hose 136 permits the nozzle arm to oscillate.

I claim:

1. In combination, a centrifugal, means for starting said centrifugal, and control means for automatically stopping said centrifugal, said control means including a valve adapted when open to release a pressure medium, means for automatically opening said valve, and means actuated by the pressure medium released by said valve for effecting the said automatic stopping of said centrifugal.

2. In combination, a centrifugal, means for starting said centrifugal, and control means for automatically stopping said centrifugal, said control means including a time controlled valve adapted when open to release a pressure medium, and means actuated by the pressure medium released by said valve for effecting the said automatic stopping of said centrifugal.

3. In combination, a centrifugal, a curbing, two troughs, a movable gate adapted to direct liquor from said curbing to either of said troughs, and control means for automatically shifting said gate from one to the other of said troughs, said control means including a time controlled valve adapted when open to release a pressure medium and means actuated by the pressure medium released by said valve for effecting the said automatic shifting of said gate.

cluding a time controlled valve adapted when open to release a pressure medium and means actuated by the pressure medium released by said valve for effecting the said automatic shifting of said gate.

4. In combination, a centrifugal, a wash fluid valve, and control means for automatically opening said wash fluid valve, said control means including a time controlled valve adapted when open to release a pressure medium, and means actuated by the pressure medium released by said time controlled valve for effecting the opening of said wash fluid valve.

5. In combination, a centrifugal, a wash fluid valve, means for automatically opening said wash fluid valve, said means including a time controlled valve adapted when open to release a pressure medium, and mechanism actuated by the pressure medium released by said time controlled valve for effecting said automatic opening of said wash fluid valve; and means for automatically stopping said centrifugal, the last said means including a time controlled valve adapted when open to release a pressure medium, and mechanism actuated by the pressure medium released by the last said time controlled valve for effecting said automatic stopping of the said centrifugal.

6. In combination, a centrifugal, a wash fluid valve, means for automatically opening said wash fluid valve, said means including a valve adapted when open to release a pressure medium, means for automatically opening the last said valve, and mechanism actuated by the pressure medium released by the last said valve for effecting the said automatic opening of said wash fluid valve; and means for automatically stopping said centrifugal, the last said means including a valve adapted when open to release a pressure medium, means for automatically opening the last said valve, and mechanism actuated by the pressure medium released by the last said valve for effecting said automatic stopping of said centrifugal.

7. In combination, a centrifugal, a curbing, two troughs, a movable gate adapted to direct liquor from said curbing to either of said troughs, and means for automatically shifting said gate from one to the other of said troughs, the last said means including an automatically actuated valve having a valve body with an inlet and outlet opening, and a movable valve stem, said stem having two valve faces and said valve body having two valve seats, the distance between said seats and faces being such as to permit said valve stem to have a limited movement in said valve body.

8. In combination, a centrifugal, a wash fluid valve, and automatic control means for automatically opening said wash fluid valve, the last said means including a valve having

a valve body with an inlet and outlet opening, and a movable valve stem, said stem having two valve faces and said valve body having two valve seats, the distance between said seats and faces being such as to permit said valve stem to have limited movement in said valve body.

9. In combination, a centrifugal, means for starting said centrifugal, and automatic control means for automatically stopping said centrifugal, the last said means including a valve having a valve body with an inlet and outlet opening, and also a movable stem, said stem having two valve faces and said valve body having two valve seats, the distance between said seats and faces being such as to permit said valve stem to have a limited movement in said valve body.

10. In combination, a centrifugal, a wash fluid valve, means for automatically opening said wash fluid valve, the last said means including an automatically actuated valve having a valve body with an inlet and outlet opening, and a movable stem, said stem having two valve faces and said valve body having two valve seats, the distance between said seats and faces being such as to permit said stem to have limited movement in said valve body; and means for automatically stopping said centrifugal, the last said means including an automatically actuated valve having a valve body with an inlet and outlet opening, and also a movable stem, said stem having two valve faces and said valve body having two valve seats, the distance between said seats and faces being such as to permit said valve stem to have a limited movement in said valve body.

11. In combination a centrifugal, means for starting and stopping said centrifugal, a cylinder and piston cooperating with the last said means, connections including a time controlled valve for supplying a pressure medium to said cylinder to stop the centrifugal after a predetermined period of time.

12. In combination a centrifugal, a curbing, two troughs, a movable gate adapted to direct liquor from said curbing to either of said troughs, a cylinder and piston cooperating with said gate, connections including a time controlled valve for supplying a pressure medium to said cylinder to shift said gate from the one trough to the other after a predetermined period of time.

13. In combination a centrifugal washing means including a wash fluid valve for washing the material in the centrifugal, a cylinder and piston cooperating with said washing means, connections including a time controlled valve for supplying a pressure medium to said cylinder to put said washing means in operation after a predetermined period of time.

14. In combination a centrifugal, driving means for driving the centrifugal, power con-

trol means for connecting and disconnecting said driving means with a power supply, a cylinder and piston cooperating with said power control means, a brake for said centrifugal, another cylinder and piston cooperating with said brake, time controlled means including a time controlled valve and connections adapted to supply a pressure medium to the first said cylinder to disconnect said driving means from said power supply after a predetermined period of time, and a connection from the first said cylinder to the second said cylinder to transmit the pressure medium to the second cylinder only after the first cylinder has been partially actuated by the pressure medium.

15. In combination a power driven centrifugal having a brake, time controlled means for automatically cutting off the power and applying the brake after a predetermined period of time, said time controlled means including a cylinder, piston, time controlled valve and connections for supplying a pressure medium to said cylinder after a predetermined period of time.

16. In combination a centrifugal, driving means for driving same, a power source, power control means for connecting and disconnecting said driving means with said power source, means cooperating with said power control means to disconnect the driving means from the power source when a pressure medium is supplied thereto, and a time controlled valve for supplying said pressure medium after the lapse of a predetermined period of time.

17. In combination a centrifugal, a curbing, two troughs, a movable gate adapted to direct liquor from said curbing to either of said troughs, a cylinder and piston cooperating with said gate, a time controlled valve for supplying a pressure medium to said cylinder to shift said gate from one trough to the other after a predetermined period of time, said time controlled valve having a valve body with an inlet and outlet opening and also a movable stem, said stem having two valve faces, and said valve body having two valve seats between said faces, the distance between said seats being so related to the distance between said valve faces as to permit said stem to have a straight line movement limited by the butting of said valve faces against said valve seats.

18. In combination a centrifugal, washing means including a wash fluid valve for washing the material in said centrifugal, a cylinder and piston cooperating with said washing means for opening said wash fluid valve, and a time controlled valve for supplying a pressure medium to said cylinder to actuate same after a predetermined period of time, said time controlled valve having a valve body with an inlet and outlet opening and also a movable stem, said stem having two valve

faces, and said valve body having two valve seats between said faces, the distance between said seats being so related to the distance between said valve faces as to permit said stem to have a straight line movement limited by the butting of said valve faces against said valve seats.

19. In combination a centrifugal machine including a vertical spindle and a pulley securely attached thereto, driving means for driving same comprising a belt and driving pulley, a source of power comprising a constantly rotating power shaft passing loosely through the last said pulley, power control means including a clutch for operatively connecting and disconnecting said driving pulley to said constantly rotating power shaft, a brake, and time controlled means adapted to actuate said power control means to operatively disconnect said clutch from said driving pulley after the passage of a predetermined period of time and to apply said brake, said time controlled means including a cylinder and piston for actuating said power control means to disconnect said driving pulley from said power shaft and another cylinder and piston for applying said brake.

20. In combination a centrifugal machine including a vertical spindle and a pulley securely attached thereto, driving means for driving same comprising a belt and driving pulley, a source of power comprising a constantly rotating power shaft passing loosely through the last said pulley, power control means including a clutch for operatively connecting and disconnecting said driving pulley to said constantly rotating power shaft, a brake, and time controlled means adapted to actuate said power control means to operatively disconnect said clutch from said driving pulley after the passage of a predetermined period of time and to apply said brake, said time controlled means including a time controlled valve, a cylinder and piston for actuating said power control means to disconnect said driving pulley from said power shaft, another cylinder and piston for applying said brake, and connections for supplying a pressure medium through said valve to the first said cylinder and piston to actuate same, and connections from the latter cylinder to the second said cylinder, the last said connections being arranged to transmit the pressure medium to the second said cylinder only after the first said cylinder has been partly actuated by the pressure medium.

21. In combination a centrifugal machine including a vertical spindle and a pulley securely attached thereto, driving means for driving same, comprising a belt and driving pulley, a source of power comprising a constantly rotating power shaft passing loosely through the last said pulley, power control means including a clutch for operatively connecting and disconnecting said driving pul-

ley to said constantly rotating power shaft, and time controlled means adapted to actuate said power control means to operatively disconnect said clutch from said driving pulley after the passage of a predetermined period of time.

22. In combination a centrifugal machine, driving means for driving same, means for connecting and disconnecting said driving means to a power supply, and time controlled means adapted to disconnect said driving means from said power supply after the passage of a predetermined period of time, said time controlled means including a cylinder and piston, a timing reservoir, means for supplying a fluid to said reservoir to progressively raise the fluid level therein, a float in said reservoir, a valve actuated by said float, and connections for supplying a pressure medium through said valve into said cylinder to actuate said piston after the predetermined period of time.

23. In combination a centrifugal machine adapted to centrifuge material charged therein, driving means for driving same, means for connecting and disconnecting said driving means to a power supply, a brake adapted to bring said centrifugal to rest, washing means for washing the materials in said centrifugal, a cylinder and piston for starting said washing means in the performance of its washing function, another cylinder and piston for disconnecting said driving means from said power supply, and time measuring means for energizing both said cylinders, said time measuring means including a timing reservoir, means for supplying fluid to said reservoir for progressively raising the fluid level therein, two valves, two floats in said reservoir and respectively adapted to actuate said valves, and connections from one of said valves to one of the aforesaid cylinders and connections from the other of said valves to the other of the aforesaid cylinders, said connections being adapted to supply a pressure medium through said valves to said cylinders for energizing same.

24. In combination a centrifugal machine, driving means for driving same, a power source, power control means for connecting and disconnecting said driving means with said power source, disengaging means adapted to actuate said power control means to disconnect the driving means from the power source when a pressure medium is supplied to said disengaging means, and a time controlled valve for supplying a pressure medium to said disengaging means after the lapse of a predetermined period of time, said valve having a valve body with an inlet and outlet opening and also a movable stem, said stem having two valve faces, and said valve body having two valve seats between said faces, the distance between said seats being so related to the distance between said valve faces as to

permit said stem to have a straight line movement limited by the butting of said valve faces against said valve seats.

25. In combination a centrifugal machine adapted to centrifuge material charged therein, means for washing the material in said centrifugal machine, a curbing, two troughs, a movable gate adapted to direct liquor from said curbing into either of said troughs, and adjustable time controlled means adapted to start water flowing through said washing means after a predetermined period of time, and means adapted to shift said gate

from one trough to the other at a time substantially later than the instant at which the 15 water commences to flow through said washing means the deferred shifting of said gate permitting more complete drainage of the original liquor from said curbing into the first trough before the gate is shifted to the 20 second trough.

In testimony whereof, I have executed this presents in the city and State of New York, on this 28th day of April, 1927.

ROBERT ALEXANDER STEPS.
